ABRAHAM POSNER, OF NEW YORK, N. Y.

ANKLE-STAY FOR SHOES.

No. 874,862.

Specification of Letters Patent.

Patented Dec. 24, 1907.

Application filed June 4, 1907. Serial No. 377,191.

To all whom it may concern:

Be it known that I, ABRAHAM POSNER, a citizen of the United States, and a resident of the city of New York, borough of Brooklyn, 5 in the county of Kings and State of New York, have invented a new and Improved Ankle-Stay for Shoes, of which the following is a full, clear, and exact description.

The invention relates to stays for the ankle 10 portions of shoes, such as shown and described in Letters Patent of the United States, No. 555,328, granted to me on February 25, 1896.

The object of the present invention is to 15 provide a new and improved ankle stay for shoes, which is simple and durable in construction and arranged to permit of conveniently placing it in position in the shoe, to properly support or stay a weak ankle of the 20 wearer of the shoe, at the same time maintaining the stay at all times in proper position and preventing undue binding at the back of the foot above the heel.

The invention consists of novel features 25 and parts and combinations of the same, which will be more fully described hereinafter and then pointed out in the claims.

A practical embodiment of the invention is 30 represented in the accompanying drawings forming a part of this specification, in which similar characters of reference indicate corresponding parts in all the views.

Figure 1 is a longitudinal sectional elevation 35 of the improvement as applied, part of the shoe being shown in section and part in elevation; Fig. 2 is a face view of the improvement, parts of the stiffener pockets being broken out; Fig. 3 is a transverse section of the same on the line 3—3 of Fig. 2, and 40 Fig. 4 is a perspective view of an ankle stay having an elastic cross band for engagement by the foot of the wearer to hold the stay in place.

The improved ankle stay has its body A 45 made of a suitable flexible material such as leather covered at the outer face with canvas, and in the said body A are arranged side pockets B running up and down in an approximately vertical direction, and each containing a stiffener C of spring metal, whalebone or other similar material, and in the lower end of the said body A is formed a pocket D for containing a stiffener E of steel, whalebone or a similar material. The body 50 A has a cut out portion A' at the rear and extending from the top of the body to approxi-

mately the middle thereof, so that when the stay is placed in position in the shoe F, as illustrated in Fig. 1, then the cut out portion A' is at the rear of the wearer's foot above 60 the heel thereof, to prevent undue binding of the stay on the wearer's foot at the portion referred to. When placing the ankle stay in position in the shoe, the lower edge thereof rests on the inside of the sole of the shoe 65 while the upper end of the ankle stay is tucked in under a top flange F', arranged on the inside of the shoe, as plainly indicated in Fig. 1. In case the ankle stay is to be used on shoes without such a flange F', then an 70 elastic band G is provided attached to the sides of the body A at the lower end thereof, to hold the stay in a bent position and to allow the stay to readily conform to the shape of the shoe. Now when the ankle stay is in 75 place in the shoe, the foot of the wearer rests on top of the elastic band G, thus preventing the stay from upward movement in the shoe while the latter is worn.

It is understood that by having the stiffeners C at the side of the ankle of the wearer of the shoe, the ankle is properly supported or stayed, and by having the stiffener E at the lower end of the stay, the latter readily conforms to the shape of the shoe and at the 80 same time assists in holding the stay in place in the shoe, by firmly pressing the lower end of the body A in firm contact with the upper of the shoe, owing to the inherent elasticity of the stiffener E.

The ankle stay shown and described is 85 very simple and durable in construction, and can be readily placed in position in the shoe, or removed therefrom, whenever it is desired to do so.

Having thus described my invention, I 90 claim as new and desire to secure by Letters Patent:

1. An ankle stay comprising a face of leather and lining of canvas secured together at their edges, said stay having a portion adapted to rest upon each side of the ankle, said portions being each provided with a plurality of vertical parallel pockets, and said stay being provided with a horizontal 100 pocket at the bottom extending across the width thereof, stiffening members in each of the pockets, said stay being cut away at the back of the shoe approximately to the vertical center, and an elastic connecting the 105 lower corners of the stay.

2. An ankle stay comprising a face of

leather and a lining of canvas secured together at their edges, said stay having a portion adapted to rest upon each side of the ankle, said portions being each provided 5 with a plurality of vertical parallel pockets, and said stay being provided with a horizontal pocket at the bottom extending across the width thereof, stiffening members in each of the pockets, said stay being cut away 10 at the back of the shoe approximately to the vertical center.

3. An ankle stay comprising a flexible body having a portion adapted to rest upon each side of the ankle, a plurality of vertical 15 stiffeners arranged in each ankle portion and extending from the top to the bottom thereof, and a horizontal resilient strip at the bottom of the stay and extending the full

width thereof, said stay being cut away at the back from the top approximately to the 20 vertical center.

4. An ankle stay comprising a flexible body having a portion adapted to rest upon each side of the ankle, a plurality of vertical stiffeners arranged in each ankle portion and 25 extending from the top to the bottom thereof, a horizontal resilient strip at the bottom of the stay and extending the full width thereof.

In testimony whereof I have signed my name to this specification in the presence of 30 two subscribing witnesses.

ABRAHAM POSNER.
